UNITED STATES PATENT OFFICE

167,874

SLIDE VIEWER

Michael S. Wolk, Miller, Ind.

Application June 9, 1952, Serial No. 20,085

Term of patent 14 years

(Cl. D61—1)

To all whom it may concern:

Be it known that I, Michael S. Wolk, a citizen of the United States, and resident of Miller, county of Lake, and State of Indiana, have invented a new, original, and ornamental Design for a Slide Viewer, of which the following is a specification, reference being had to the accompanying drawing, forming a part thereof.

Figure 1 is a perspective view of a slide viewer, showing my design;

Figure 2 is a perspective view thereof showing the back and one side thereof;

Figure 3 is an exploded view thereof showing the front and one side of the base and the cover with the cover removed.

I claim:

The ornamental design for a slide viewer, substantially as shown.

MICHAEL S. WOLK.
